Primary Examiner — Cathron Brooks*Assistant Examiner* — Cary M Robinson(74) Attorney, Agent, or Firm — McAndrews Held & Malloy, Ltd.(57) CLAIM

The ornamental design for a display screen or portion thereof with graphical user interface, as shown and described.

DESCRIPTION

The FIGURE is a front view of a display screen or portion thereof with graphical user interface, showing our new design.

The outermost dashed broken lines illustrate portions of the display screen or portion thereof and form no part of the claimed design. The remainder of the dashed broken lines illustrate portions of the graphical user interface and form no part of the claimed design.

1 Claim, 1 Drawing Sheet(56)
